HOUSEHOLD SCALE

Harold O. Friedrich, Lake Geneva, Wis., assignor to American Family Scale Company, Inc., Chicago, Ill., a corporation of Illinois

Filed Mar. 24, 1964, Ser. No. 79,157

Term of patent 14 years

(Cl. D52—10)

Fig. 1.

Fig. 2.

Fig. 3.

Fig. 4.

FIG. 1 is a side elevational view of a household scale, showing my new design;

FIG. 2 is a front elevational view thereof;

FIG. 3 is a top plan view thereof;

FIG. 4 is a rear elevational view thereof.

The undisclosed side of the household scale is a mirror image of the side shown.

I claim:

The ornamental design for a household scale, as shown and described.
